UNITED STATES PATENT OFFICE.

JOSEPH MANEGOLD AND FRANK MANEGOLD, OF SAN FRANCISCO, CALIFORNIA; SAID
JOSEPH MANEGOLD ASSIGNOR TO SAID FRANK MANEGOLD.

SLIDING SIDELIGHT FOR AUTOMOBILES.

Application filed January 11, 1923. Serial No. 611,953.

To all whom it may concern:

Be it known that we, JOSEPH MANEGOLD and FRANK MANEGOLD, citizens of the United States, residing in the city and county of San Francisco and State of California, have invented a new and useful Improvement in Sliding Sidelights for Automobiles, of which the following is a specification.

Our invention relates to improvements in sliding sidelights for automobiles and the like and particularly to an improved construction whereby a closed car effect can be obtained without the use of glass.

The primary object of our invention is to provide an improved sidelight for automobiles and the like.

Another object is to provide an improved construction whereby the mounting and manipulation of the sidelights may be facilitated.

A further object is to provide an improved construction whereby the sidelights may be maintained in any desired position.

Another object is to provide an improved sliding sidelight formed from a flexible transparent substance adapted to reduce danger to the occupants of an automobile in case of accident.

Another object is to provide an improved side curtain which may be readily mounted in connection with existing tops and bodies.

A still further object is to provide improved means for preventing the entrance of wind, rain and the like between adjacent sidelights.

A still further object is to provide an improved construction which may be built and installed at an economical cost.

40 We accomplish these and other objects by means of the device disclosed in the drawings forming a part of the present specification and drawings wherein like characters of reference are used to designate similar parts throughout said specification and drawings and in which:

Fig. 1 is a broken side elevation of an automobile equipped with my improved sliding sidelights.

50 Fig. 2 is a broken side elevation of one sidelight showing the manner in which the upper guide is engaged.

Fig. 3 is an enlarged section taken upon the line 3-3 of Fig. 1.

55 Fig. 4 is a horizontal section taken upon

the line 4-4 of Fig. 3, showing the relation between adjacent sidelights and the weather strips secured therebetween.

Fig. 5 is a broken side elevation of a sidelight showing a modified construction of the springs and means for attaching the sidelights upon the upper guide.

Referring to the drawings the numeral 1 is used to designate in general the body of an automobile provided with a top 2 of the type commonly provided on open car models. As is well known, the side curtains commonly provided for use with tops of the type disclosed can be secured in position only with great inconvenience, and even when so secured are not effective in completely excluding wind, rain and the like to obtain the comfort of a closed car model. Furthermore the curtains cannot be adjusted to various positions, and when not in use are commonly stored in an inaccessible portion of the automobile so that much inconvenience is caused when it becomes necessary to mount the curtains in position.

To overcome the above objections, tops have been built onto bodies to replace the standard tops with which the open car models are equipped, such structures being heavy wooden or metal structures having glass windows arranged to be moved from a normally open position within the back portion of the top, to closed positions along the sides of the automobile. Such arrangement not only adds excessively to the weight of the automobile, but the cost of such installation is so great as to be prohibitive to persons of moderate means. Furthermore, the large pieces of glass used are a source of great danger should an accident occur, many persons preferring the relative discomfort of an open car to exposing themselves to this hazard when driving.

To overcome the objections to both the above mentioned types of automobile tops we have devised an improved arrangement wherein sidelights 3 are mounted for slideable movement in connection with the standard open car top. The sidelights 3 are formed from substantially rectangular frames 4 formed from sheet metal or other suitable material adapted to obtain a rigid frame. Sheets 5 of transparent celluloid, isinglass, or other suitable flexible substance are cut to a size slightly less than the size

of the opening within each frame. Binding strips 6 are then mounted over the frame in such manner that the opposite edges of the strips will be disposed upon 5 opposite sides of the transparent sheets 5 within the openings of the frame, said strips extending entirely around and completely enclosing the frame. The edges of the strips 6 are then stitched together by means 10 of stitches 7 passed through the sheets 5 so that the sheets are firmly sewed in position within the frames. Additional stitches 9 may be sewed through the strips close to the frame 4 to add firmness to the side- 15 light, and to prevent slippage of the binding strips over the frame.

Brackets 11 are screwed or otherwise secured upon the upper corners of the frames 4 to engage upper guides 12 secured upon 20 the inner sides of the side members 13 of the top 2. The guides 12 are preferably formed from channel members secured upon strips 14 adapted to be bolted or otherwise secured upon the main bow of the top as 25 best shown in Fig. 3 of the drawings, this construction is, of course, subject to variation to meet the requirements of different types and structures of tops. The channels are provided with inwardly turned flanges 30 16 formed upon the lower ends of the legs, said flanges being spaced from the back of the channel sufficiently to receive lateral extensions 17 carried upon the upper end of the brackets 11 whereby said brackets may 35 be retained in engagement with the guides. The guides are mounted in pairs upon each side of the top in such manner that when a sidelight is mounted in each guide such sidelights will be slightly spaced as shown 40 in Fig. 4 of the drawings to permit independent movement thereof.

Lower guides 18 are secured upon the upper edges of the sides of the body by screws or other suitable securing means, 45 said guides being built up to a height sufficient to permit the sidelights to be moved to the extreme back of the body. Channels are provided to receive the lower edges of the sidelights which are arranged to fit 50 neatly between the upper and lower guides when assembled into the sides of the automobile.

A shield 19 provided with a flexible transparent pane is secured upon each side of 55 the automobile adjacent the forward end of the top to effect a permanent closure between the adjacent sidelights and the windshield of the automobile when said sidelight is moved to the closed position. A curtain 60 21 is permanently secured at the back of the top to extend between the top and the upper edge of the body, said curtain being of sufficient width to normally cover the sidelights 3 when moved to the rearward position.

65 Leaf springs 22 are secured upon the

upper ends of the brackets 11 within the upper guides 12 to normally exert a pressure against the back of said guides. The springs may be riveted or welded to the brackets or secured in other suitable manner adapted to give a rigid connection. The pressure exerted by the springs is sufficient to resiliently maintain the sidelights at any desired portion of the sides of the automobile to be closed. Depressions 23 may be provided in the back of the channel guides 12 to receive the ends of the springs when the sidelights are moved to their extreme positions. The springs 22 are normally enclosed between the sidelights and the backs of the adjacent channel guides. If desired the spring may be made of sufficient width to be engaged by the flanges 16 and thereby made to serve the purpose of the extensions 17 in maintaining engagement between the sidelights and the guides. This construction is shown in Fig. 5 of the drawings wherein the spring is shown secured upon the top of the bracket 11 in such manner that the sides of the spring along the middle portion thereof engage the flanges 16 and the ends of the springs engage the back of the guide to exert a pressure thereagainst to normally resist movement along the guide as above explained.

As the sidelights upon each side of the automobile are arranged in slightly spaced relation we provide a weather strip 24 arranged to prevent the entrance of wind, 100 rain and the like between the curtains. The weather strip consists of a strip of rubber or other suitable material, preferably triangular in cross section, said strip being clamped between inwardly bent legs of a channel 27 screwed or otherwise secured upon one side 105 of a frame 4 to engage the surface of the adjacent sidelight. The outer edge of the strip 24 is arranged to press firmly against the adjacent curtain but is sufficiently flexible to be readily bent to permit movement 110 of either sidelight in either direction.

From the above description it will be seen that we have provided an improved construction whereby sidelights may be constructed without the use of glass and readily 115 installed in connection with existing types of tops and open car bodies to obtain a closed car effect at a moderate cost. The several parts are, of course, subject to modification in the details of construction and installation to conform to different styles of tops and bodies. We, therefore, do not wish to restrict ourselves closely to the precise details shown, but desire to avail ourselves 120 of such reasonable modifications as may fall within the scope of the appended claims.

Having thus described our invention what we claim as new and desire to secure by Letters Patent is:

1. The combination with an automobile 130

- body and top, of a pair of strips bolted in proximate parallel relation upon the inner sides of the side members of the top; channels forming upper guides secured upon the 5 lower edges of the strips upon both sides of the top, said channels having inwardly disposed retaining flanges; lower guides secured upon the upper edges of the body; sidelights slidably mounted between the upper and lower guides; brackets secured upon the sidelights adjacent the upper corners thereof; extensions formed upon both sides of each bracket and engaged within the upper guides, said extensions being retained 10 in engagement with the guides by the retaining flanges thereof; springs each having one end secured to a bracket and the other end resiliently engaging the top of the channel guides to hold the extensions against 15 the flanges and thereby retain the sidelights in desired positions.
2. The combination with an automobile body and top, of a pair of strips bolted in proximate parallel relation upon the inner 20 sides of the side members of the top; channel forming upper guides secured upon the 25 lower edges of the strips upon both sides of the top, said channels having inwardly disposed retaining flanges; lower guides secured upon the upper edges of the body; sidelights slidably mounted between the upper and lower guides; brackets secured upon the sidelights adjacent the upper corners thereof; extensions formed upon both sides of each bracket and engaged within the upper guides, said extensions being retained in engagement with the guides by the retaining flanges thereof; springs each having one end secured to a bracket and the other end resiliently engaging the top of the channel guides to hold the extensions against the flanges and thereby retain the sidelights in desired positions, depressions being formed in the top of the channels to engage the ends of the springs and define the extreme positions of the sidelights and increase the resistance offered by the springs to movement from said extreme position.

In witness whereof we hereunto set our signatures.

JOSEPH MANEGOLD.
FRANK MANEGOLD.
